CLAIM

The ornamental design for a cosmetic brush with handle, as shown and described.

DESCRIPTION

FIG. 1 is a perspective view of an exemplary embodiment of a cosmetic brush with handle showing my new design; FIG. 2 is a left side view of the cosmetic brush with handle of FIG. 1;

FIG. 3 is a right side view of the cosmetic brush with handle of FIG. 1;

FIG. 4 is a bottom plan view of the cosmetic brush with handle of FIG. 1;

FIG. 5 is a top plan view of the cosmetic brush with handle of FIG. 1;

FIG. 6 is a front side view of the cosmetic brush with handle of FIG. 1; and,

FIG. 7 is a rear side view of the cosmetic brush with handle of FIG. 1.

That portion(s) of the cosmetic brush with handle shown in broken lines is for environmental purposes only and does not form part of the claimed design.
